(57) **CLAIM**

I claim the ornamental design for a behind-the-ear sound processor, as shown and described.

DESCRIPTION

FIG. 1 is a rear perspective view of a behind-the-ear sound processor constructed in accordance with one embodiment of the present invention;

FIG. 2 is a front elevation view thereof;

FIG. 3 is a rear elevation view thereof;

FIG. 4 is a top side elevation view thereof;

FIG. 5 is a left side elevation view thereof;

FIG. 6 is a bottom side elevation view thereof;

FIG. 7 is an exploded rear perspective view thereof;

FIG. 8 is an exploded front elevation view thereof;

FIG. 9 is an exploded rear elevation view thereof;

FIG. 10 is an exploded top side elevation view thereof;

FIG. 11 is an exploded left side elevation view thereof; and,

FIG. 12 is an exploded bottom side elevation view thereof.

The broken lines in the drawings are included for the purpose of illustrating portions of an article that form no part of the claimed design.
